[57] CLAIM

The ornamental design for a combined grass catcher blower and chute, as shown and described.

DESCRIPTION

FIG. 1 is a perspective view of a combined grass catcher blower and chute showing my new design;

FIG. 2 is a top view thereof;

FIG. 3 is a bottom view thereof;

FIG. 4 is a front elevational view thereof;

FIG. 5 is a left side elevational view thereof;

FIG. 6 is a right side elevational view thereof;

FIG. 7 is a rear elevational view thereof;

FIG. 8 is a perspective view of a second embodiment of FIG. 1;
FIG. 9 is a top view of FIG. 8;
FIG. 10 is a bottom view of FIG. 8;

FIG. 11 is a front elevational view of FIG. 8;
FIG. 12 is a left side elevational view of FIG. 8;
FIG. 13 is a right side elevational view of FIG. 8;
FIG. 14 is a rear elevational view of FIG. 8.

FIG. 1**FIG. 2****FIG. 3****FIG. 4****FIG. 5**

FIG. 6**FIG. 7**

FIG. 8**FIG. 9****FIG. 10****FIG. 11****FIG. 12**

FIG. 13

FIG. 14
